US00D373161S

United States Patent [19]

Schmidt et al.

[11] **Patent Number:** Des. 373,161[45] **Date of Patent:** **Aug. 27, 1996[54] **GOLF PUTTER HEAD WITH FACE PLATE
INSERT**[76] Inventors: **Glenn H. Schmidt**, 1409 Schueren Rd.,
Malibu, Calif. 90265; **Richard C.
Helmstetter**, 2285 Rutherford Rd.,
Carlsbad, Calif. 92008-8815[**] Term: **14 Years**[21] Appl. No.: **30,464**[22] Filed: **Oct. 31, 1994****Related U.S. Application Data**[63] Continuation-in-part of Ser. No. 24,688, Jun. 20, 1994,
which is a continuation-in-part of Ser. No. 16,187, Dec. 9,
1993.[52] **U.S. Cl.** ..... **D21/219**[58] **Field of Search** D21/217-219;
273/167-175[56] **References Cited**
